UNITED STATES PATENT OFFICE.

PHILIP D. PARSONS, OF PHILADELPHIA, PENNSYLVANIA, ASSIGNOR, BY MESNE ASSIGNMENTS, TO SCOTT PAPER COMPANY, A CORPORATION OF PENNSYLVANIA, (1922.)

COIN-CONTROLLED DISPENSING MACHINE.

Application filed September 10, 1920. Serial No. 409,348.

My invention has for an object mechanism, preferably coin-controlled, for enabling paper towels and other articles, arranged within a cabinet, to be dispensed in regulated quantities; and in the preferred construction of the mechanism, I make the operative parts in such form and adapt them to cooperate in such manner that upon one or more coins being deposited before operation, the mechanism may be operated repeatedly, once for each coin deposited preliminary to the operation, the devices acting to discharge or deliver a towel or article with each operation.

My object is further to provide a construction of coin operated mechanism which is adapted, by slight change, easily and quickly made, to suit coins of different countries, so that the machines as they come from the factory may be readily adjusted for the particular coin to be employed as the controlling means.

My object is further to so construct the operating parts that they are few and simple in structure and can readily be removed and replaced or substituted in part or in whole without the necessity of any tools.

With the above and other objects in view, the nature of which will be more fully understood from the description hereinafter, the invention consists in the novel construction of coin controlled dispensing machines, as hereinafter more fully described and defined in the claims.

In the drawings: Fig. 1 is a front view of a dispensing machine embodying my invention having the upper portion broken away; Fig. 2 is an end view of the same with the end portion broken away to show the interior details; Fig. 3 is a sectional view, similar to Fig. 2, but with the coin-controlled mechanism shown at the completion of its discharging movement; Fig. 4 is a perspective view of the coin-controlled mechanism separated from the case; and Fig. 5 is an end view of the ejector cylinder.

2 is the case and may be made of any shape desired, but in the particular example, here shown, it is made rectangular in form and suitable for receiving a stack of folded paper towels 6, in any number desired, arranged one above the other and from which the lowermost towel is discharged at each operation. The lower part of the case is

provided at its rear with an inwardly directed shelf 3, which preferably inclines upward and terminates in a beaded part 3^a which acts as a support for the towels near their middle and throughout their length, 60 the shelf insuring a firm support for as many towels in the stack as may be desired. The forward portion of the bottom part of the case is provided with a second inclined shelf 4 which extends backward and downward and terminates in a beaded edge 5, said shelf 4 acting to support the stack of towels at their forward portions but so as to permit one of the under flaps 8 of the lowermost towel to fall by gravity and be 70 sustained in position upon and so as to be received by the rotary ejector. The ejector comprises the cylindrical body 9 secured upon heads 13 fastened to the shaft 14 journaled in the casing, the said body being slit 75 along its length to form the outwardly extending jaw 11 and the inwardly bent flange 10 and providing between them the longitudinal throat 12 to receive the flap 8 of the towel when the ejector is rotated. 15 is a 80 coil spring arranged about shaft 14, having one end connected with one of the heads 13 of the ejector and the other end connected with the main case, so that normally the ejector is returned to the position shown in 85 Fig. 2 with the jaw 11 resting against the beaded edge 3^a of the shelf 3. The rotary ejector 9 is operated by the mechanism to be now described.

The end of the ejector shaft 14 is provided with a pinion 16. Meshing with the pinion 16 is a driving gear 17 provided with sufficient teeth to give the pinion and ejector approximately three-quarters of a revolution as a minimum. The driving gear 17 is provided with a wing nut 20 by which to rotate it and also has a coin slot 18 through it, providing a runway 36 for the coin deposited through the slot 19 in the front plate 126 of the case. Normally, the slot in the 100 gear 17 is inclined so that the coin will roll backward through the gear to a position in front of the pinion 16 and coin carrier gear 21, as indicated in dotted lines in Fig. 2. If one or more coins are in the slot 18 of the 105 gear 17 and the said gear should be rotated, the said coins cannot escape as they cannot fall downward by reason of the runway 36, or when the slot 18 is vertical by the part 35^a which forms a curved floor beneath the 110

2
said gear and slot thereof. Coin carrying gear 21 is provided with teeth engaging the pinion 16 and is driven by said pinion and hence rotates in the same direction as the operating or driving gear 17; it is journaled upon a stud 22 and has a slot 23 into which a fixed pin 24 extends to limit the extent of its rotary movements. This is not so material in the normal position because the jaw 11 of the ejector 9 acts to stop rotation of pinion 16 by contact with shelf 3 (Fig. 2), but in the ejecting movement (Fig. 3), it is important that the parts shall be arrested at the proper time and this is insured by contact of the end of slot 23 with the pin 24. The gear 21 is further provided with the coin stop 25 made in the form of a lateral flange against the end of which the coin rests, as shown in Fig. 2; and moreover, the lower portion of this gear is provided with the coin guide floor 34 upon which the coin rests, as indicated, said floor also providing a runway for coins or slugs of smaller diameter which may be inserted in the machine and whose presence are not intended to be capable of operating the mechanism. In case of the deposit of these smaller coins or slugs, they pass the gear 21 and leaving the runway thereof are received upon the guide 32 by which they are directed into the coin drawer 33, which has a portion divided off for receiving them.

Referring again to the coin carrier gear 21, it will be noted that in addition to the operating teeth 37 to insure its rotation, it has a wide space or gap between the teeth 37 and 38 for operation with pawl 29 and teeth 39 (together with teeth 38) for operation with pawl 27, which latter insures complete or full forward rotary movement and discharge of a coin which is in the custody of the gear 21, while pawl 29 is to prevent forward movement to the carrier when no coin is present. The pawls 27 and 29 are preferably each pivoted upon the same stud 28 and are so arranged that when pawl 29 is down to engage the space or gap between the teeth 37 or 38, the pawl 27 is held up clear of the teeth 39 and high enough for tooth 26 to pass, and vice versa, pawl 27 acting as a means for preventing backward rotation of the carrier 21 except when there is no coin present. It will further be noted that the gear 21 is provided with a high tooth 26 which normally holds the pawl 29 up (Fig. 2), the particular function of this being to also hold up the part 30 of this pawl to permit the coin to roll into position against the stop 25 and position itself under the said part 30 of the pawl. The high tooth 26 does not directly act on the pawl 27, so that, as shown in Figs. 2 and 4, it is free to engage the teeth 39. It will now be understood that when the carrier gear 21 is rotated clockwise with the coin in position (Fig. 2), the

high tooth 26 releases the pawl 29 but part 30 thereof then rests upon the coin and hence cannot fall sufficiently to enable the pawl to engage the teeth 37 or 38. The discharging movement may, therefore, continue with the other pawl 27 acting freely and trailing over the teeth 39, 26 and 38 of gear 21, and thus prevent the back movement of the carrier while the coin is in transit. When the positions of the parts reach those indicated in Fig. 3, the coin is thrown onto the coin guide 31 of the case and by it guided down into the drawer 33. The discharge of the coin releases the part 30 and with it the pawl 29 which falls and rests upon the teeth 37 and 38, and, at the same time, by its superior weight, it engages and lifts pawl 27 clear of the teeth of the gear 21 and permits it to rotate backward to its initial position where it is again lifted by the high tooth 26 (Fig. 2). It will be seen that the pawl 27 requires the ejecting movement to continue until completed and the coin deposited in drawer 33, so that only one towel will be delivered for one coin; and pawl 29 prevents rotation of carrier gear 21 and the operation of the ejector 9 if no coin has been deposited and retained against the stop 25. Should an attempt be made to eject a towel without depositing the coin, the high tooth 26 will be moved to quickly allow the pawl 29 to engage the wide gap between the teeth 37 and 38 and prevent more than a very slight rotation of the ejector and carrier gear before the pawl engages teeth 37 to prevent further rotation; and when the handle 20 is released, the spring 15 returns the high tooth again under the pawl 29, as shown in Fig. 2, so that the parts are automatic.

More particularly referring to the two pawls 29 and 27, it is to be understood that these pawls, while pivoted upon the same pin or stud 28, are independently movable about said pin as a fulcrum. They, however, contact with each other adjacent to the pin in such a manner that when the pawl 29 fully drops by gravity, it operates to lift the lighter pawl 27 clear of the teeth on the carrier gear 21, so that said gear may be rotated anticlockwise to reset the carrier to receive another coin. When, however, the pawl 29 is lifted out of the wide space or gap between the teeth 37 and 38, whether it is raised by the high tooth 26, as in Fig. 2, or by the coin in passing, the pawl 27 is then free to fall by gravity into engagement with the teeth on the carrier gear 21 and to act as a full stroke pawl, as shown in Fig. 2, to prevent anticlockwise movement of the carrier gear. This necessitates the carrier gear being moved clockwise to the full extent, as in Fig. 3, to release the coin before it can be reversed. With the coin removed, however, it ceases to be an active pawl to prevent backward movement when the car-

rier gear 21 is turned anticlockwise, because the pawl 29 drops to the position shown in Fig. 3 and this action lifts the pawl 27 out of engagement with the teeth of the carrier gear. When the carrier is further moved anticlockwise to a position in which the nose of the pawl 29 drops into the wide space or notch between the teeth 37 and 38 of the carrier gear 21, this pawl locks the carrier gear against rotation clockwise. However, at this moment the long tooth 26 presses upon the heel of the pawl 29 and raises it to the position indicated in Fig. 2, such action lowering the pawl 27 into engagement with the teeth 39 on the carrier gear.

There is room in gear 17 for two additional coins, so that three coins may be deposited, and in such event the handle 20 may be operated three times in succession, ejecting one towel at each operation.

The use of the long tooth 26 is to sufficiently raise the part 30 and its attached pawl 29 to enable the coin to pass below it until stopped by the stop flange 25 on the carrier gear. In this manner, coins much larger than those indicated in dotted lines in Figs. 2 and 3 may be permitted to enter into operative position, but if the device is intended to work only with a coin of a definite diameter, this tooth 26 may be filed down to permit the normal maximum raising of the part 30 to be just sufficient to permit the entrance of the coin. If there is no coin in position to raise the part 30, then when the carrier gear 21 is moved clockwise just sufficient to enable the tooth 26 to release the pawl 29, said pawl would fall into the wide notch or gap and engage the teeth 37 and prevent a clockwise movement of the carrier gear and hence prevent a discharge of a towel. As shown in the drawing (Fig. 2), the presence of the long tooth 26 would permit the device to be operated by an English half penny, but if it was to be used only for the American cent or other smaller sized coin, the long tooth 26 may be filed off to any degree desired to make the device operate for any desired size of coin. The long tooth, therefore, is to enable the coin lock to be readily adapted to the size of the coin to be employed and hence to suit the commercial markets of different countries.

A short bridge piece 35 is provided between the gears 17 and 21, to provide a runway for the coin from gear to gear. It will be seen that there are only four operative parts, and these are removably positioned; hence the device is exceedingly simple and not liable to become worn or get out of order. In case of breakage, repairs may readily be made by a person of ordinary intelligence. The coin operable parts are covered by an end plate 40 which may be locked or otherwise secured in position for permitting access when desired.

More particularly referring to the ejector operation, the forward rotation of the ejector receives the flap 8 of the towel in the throat 12, causing it to be bent over the jaw 11 and pulled downward, which action continues to also pull down the body of the towel back of the front plate 4 to a position above the lower shelf 41 and practically releasing the towel from the rear shelf 3 also. The return of the ejector releases the towel 75 and leaves the same in position on the shelf 41 to be removed by hand. When one towel is removed, the flap or tab 8 of the next lowermost towel falls by gravity to position shown in Fig. 2 and the operation may be 80 repeated by deposition of or presence of another coin.

The mechanism is designed to operate from any predetermined sized coin such as found in the United States and foreign 85 countries, and the adjustment is made by cutting back the stop flange 25 of gear 21 to permit the coin to enter far enough to properly cooperate with the pawl part 30 and to be carried with the gear 21 when 90 rotated.

The construction of my improved machine is such that the towels are inaccessible normally, and only one towel can be obtained for one coin. It will be understood, however, that in those cases where the machine is installed and it is not desired that pay for the towels shall be exacted, the machine may be employed for dispensing without coins by simply removing the pawls 29 and 27 or 100 the gear 21 itself, if desired.

In this application no claim is made for the cabinet or vending machine as distinguished from the details of the coin controlled lock therefor, as the same forms 105 part of my application Serial Number 542, 245, filed March 9, 1922, upon which Letters Patent No. 1,424,772, dated August 8th, 1922, was granted and constituting a division of this application.

It will now be apparent that I have devised a novel and useful construction which embodies the features of advantage enumerated as desirable, and while I have in the present instance shown and described the 115 preferred embodiment thereof which has been found in practice to give satisfactory and reliable results, it is to be understood that I do not restrict myself to the details, as the same are susceptible of modification 120 in various particulars without departing from the spirit or scope of the invention.

Having thus described my invention, what I claim as new and desire to secure by Letters Patent, is:—

1. In a machine of the character stated, a rotary oscillating operating part for whatever purpose intended, combined with a pinion thereon, a coin-controlled means for locking said rotary oscillating operating 130

part against movement except when a coin is present formed of a pivoted coin carrier having teeth meshing with the pinion of the rotary oscillating operating part and also having means for receiving and supporting a coin, a pawl for normally preventing rotation of the coin carrier but adapted to be raised to unlocking position by the coin, and a second pawl for locking the coin carrier 10 against return movement when it contains a coin, said second pawl moved out of operative position by gravity action of the first mentioned pawl.

2. In a coin controlled dispensing machine, a case for the articles having supporting means at the bottom, combined with ejecting means, a spring to normally hold the ejecting means in its initial position, and hand operable coin-controlled means for actuating the ejecting means comprising a train of gears, one of which directly actuates the ejector, another of which is provided with hand operating means and has a guide slot for the coin, and the remaining or carrier gear having means for receiving the coin and conveying it to a coin receptacle, and locking means controlled by the coin in the custody of the carrier gear to prevent the carrier gear from rotating except when the coin is present.

3. The invention according to claim 2, further provided with a pawl to prevent a return movement to the coin carrier gear until a full movement of said gear and discharge of the coin has taken place.

4. The invention according to claim 2, wherein the coin carrier gear has an inclined floor for the coin and a lateral coin stop flange at a higher elevation to contact 40 with the upper part of the normal coin, but so as to leave a clear space between it and the inclined floor to permit the free passage and discharge of coins of lesser than normal diameter.

45 5. A dispensing cabinet combined with an ejecting means, and a coin-controlled operating means comprising a plurality of disk shaped parts in geared relation, one of which is hand operated and is provided 50 with an inclined coin guide slot through

it in the plane of its rotation one end of said slot initially in alignment with a coin slot in the cabinet, and another of which disk shaped parts acts as a coin carrier and is provided with an inclined coin runway 55 or floor and a lateral stop flange at a higher level to provide a clear space between it and the runway or floor to permit passage and discharge of all coins of lesser than normal diameter, a coin-controlled pawl 60 for normally preventing the coin-carrier disk being rotated but releasing it when a coin is present.

6. The invention according to claim 5, further having the coin carrier disk provided with a high tooth for initially raising the pawl to permit the coin passing to the disk below the pawl preliminary to the dispensing operation.

7. The invention according to claim 5, further having a locking pawl for preventing a return movement to the coin carrier disk until a full movement has been made and the coin discharged.

8. The invention according to claim 7, 75 wherein the locking pawl is normally held out of action by the coin-controlled pawl except when a coin is present.

9. The invention according to claim 5, wherein the slotted portion of the hand 80 operated disk is of sufficient length to receive and hold a plurality of coins, whereby the machine may receive coins sufficient to permit a series of successive ejection of articles.

10. In a device of the character stated, a coin carrier disk having the inclined runway or floor and lateral projecting coin stop flange at a distance above the floor at a distance slightly less than the diameter of 90 the normal coin to be supported so that the coin rests against its forward edge, said flange of radially narrow thickness and adapted to be filed back to a greater or less distance to adapt the machine to coins of 95 different diameters to suit uses in different countries.

In testimony of which invention, I hereunto set my hand.

PHILIP D. PARSONS.
